INTERLOCKING CONTROL APPARATUS

Charles H. Lay, Swissvale, Pa., assignor to The Union Switch & Signal Company, Swissvale, Pa., a corporation of Pennsylvania

Application December 3, 1938, Serial No. 243,874

6 Claims. (Cl. 246—134)

My invention relates to interlocking control apparatus for railway track switches and signals in railway switching or interlocking layouts.

One feature of my invention is the provision of novel and improved means for protection against unsafe conditions which might exist when an interlocking system, which is provided with only one source of power, is again supplied with power from that source after a power interruption. Another feature of my invention is the provision of means for reducing train delays following restoration of power from the single source.

I shall describe one form of apparatus embodying my invention, and shall then point out the novel features thereof in claims.

The accompanying drawing is a diagrammatic view showing one form of apparatus embodying my invention.

Referring to the drawing, a portion of a railway interlocking layout is shown comprising two tracks interconnected by means of a crossover with switches 3 and 3a. The lower one of the two tracks, as shown in the drawing, is divided by means of insulated joints 6 in rails 1 and 1a to form two track sections comprising an approach section designated by the reference character 2RAT, and a detector section designated by the reference character 2T. The upper track, as shown in the drawing, is similarly divided by insulated joints 6 in rails 5 and 5a to form an approach section 4LAT and a detector section 4T.

Each track section is provided with a track circuit including a source of current, shown as the secondary winding of a transformer 7 connected across the rails adjacent one end of the section, and the track winding 8 of a two-element track relay, designated by the reference character R or SR with a distinguishing prefix comprising the reference character for the associated track section, connected across the rails adjacent the other end of the section. Each of the track relays, as shown, is also provided with a local element 9. The local element 9 of each of the detector section track relays 2TSR and 4TSR is provided with two pick-up circuits and a stick circuit.

A power-off stick relay, designated by the reference character POSR, has a pick-up circuit including a front contact of each of the relays 2TSR and 4TSR. The power-off relay has also a stick circuit controlled by only a front contact of the power-off relay.

Assuming that, as shown in the drawing, the direction from the left-hand end of the interlock-

ing layout toward the right-hand end is eastbound, a signal 2R is shown adjacent the entrance end of section 2T for governing eastbound traffic movements into this section. A similar signal 4L is shown adjacent the entrance end of section 4T for governing westbound traffic movements into section 4T. Each of these signals, as shown in the drawing, is of the color light type comprising a yellow lamp Y, for directing traffic movements into the corresponding track section, 10 and a red lamp R indicating stop.

Each of the signals 2R and 4L is controlled by a signal relay designated by the reference character HR with a prefix corresponding to the reference character for its signal. Each signal relay HR is controlled by a contact of the track relay for the detector section into which its signal directs traffic movements, and by a reverse contact of a manually operable signal lever designated by the reference character V with a prefix 15 corresponding to the number in the reference character for the associated signal.

As shown in the drawing, each of the signal levers 2V and 4V has a center or normal position N, a reverse position L to the left which can 25 be used for controlling a westbound signal, a normal lock or indication position B to the left, a reverse position R to the right, and a normal lock or indication position D to the right. In the drawing, however, each of the levers 2V and 4V 30 is shown controlling a signal for only one direction of traffic movement, but could also be used for controlling a signal for the opposite direction of traffic movement.

In the drawing, four contacts are shown operated by each of the levers 2V and 4V. Adjacent the symbol for each of the contacts of the signal levers V, a reference character is placed to indicate the position or positions of the associated lever at which each of these contacts is closed. 35 For example, the letter N adjacent contact 23 of lever 2V means that contact 23 is closed when lever 2V is in its N position only; letter R adjacent contact 28 of lever 2V means that contact 28 is closed only when the lever is in its reverse 40 position R; the letter D adjacent contact 34 of lever 2V means that contact 34 is closed only when lever 2V is in the D position; and the letters NL adjacent contact 13 of lever 2V mean that contact 13 of lever 2V is closed when lever 45 2V is in the N position or the L position or at any point between these two positions.

Each of the signal levers 2V and 4V can be returned to its N position from either its L or its R position only when an associated electric 50

55

lock winding is energized. Each of these electric lock windings is designated by the reference character M with a prefix corresponding to that of its lever. Each electric lock winding M controls a locking dog 10 which, in turn, controls movements of a locking segment 11 which is provided with a lug 12.

Each segment 11 is mechanically connected with its lever V, as indicated in the drawing by a dash line. One manner of connecting each segment 11 with its lever V is such that when the associated lever V is moved to the left, the segment 11 will be moved to the right, or if the lever V is moved to the right, the segment 11 will be moved to the left. When signal lever 2V or 4V is moved to its reverse position R or L, respectively, the electric lock winding M for the associated lever will be deenergized, and hence the dog 10 controlled by that winding M will rest on the corresponding segment 11, and when an attempt is made to return the lever to its N position, dog 10 will engage the corresponding lug 12 when the lever reaches its position D or B, respectively, and will thus prevent complete return 25 of the lever to the N position until the associated winding M is again energized.

Because, in the drawing, lever 2V is shown controlling only an eastbound signal, its electric lock winding 2M is energized by each of its three control circuits shown only when lever 2V is in its lock position D. Similarly, lever 4V is shown controlling only a west bound signal, and hence its electric lock winding 4M is energized by each of its three control circuits shown only when lever 4V is in its lock position B.

Switches 3 and 3a are operated by mechanisms 3W and 3AW, respectively. These mechanisms are controlled in multiple by an electrical circuit which includes contacts 23 and 24 of levers 2V and 4V, respectively, and pole changing contacts 22 and 25 of a manually operable switch control lever 3V. Lever 3V, as shown, has only a normal position N to the left, and a reverse position R to the right, corresponding to the 45 normal and reverse positions, respectively, of switches 3 and 3a.

The primary windings of transformers 1, the local windings 9 of relays 2TSR, 4TSR, 2RATR and 4LATR, the electric lock windings M of levers 2V and 4V, the signal control relays 2RHR and 4LHR, power-off relay POSR, signal lamps Y and R, and switch mechanisms 3W and 3AW are all energized by current from a single source of power, not shown in the drawing but having terminals BX and CX. This source may, for example, be some suitable source of alternating current.

The contacts operated by the various relays and signal levers are identified by numbers, each 60 such number having a distinguishing prefix from which it is separated by a dash when the contacts are shown apart from the relays by which they are operated. The prefix for each of these contact numbers comprises the reference character for the relay by which it is operated. For example, contact 2RHR-30 in the circuits for electric lock winding 2M is identified by the number 65 30 separated by a dash from the prefix 2RHR which is the reference character for relay 2RHR by which this contact is operated.

Having described in general the arrangement and control of the various parts of one form of apparatus embodying my invention, I shall now describe in detail the operation of the apparatus.

As shown in the drawing, all parts of the appa-

ratus are in the normal condition, that is, the various track sections are unoccupied and hence the track relays R and SR are energized; switch and signal control levers V are in the normal or N position, and hence the normal control circuit for mechanisms 3W and 3AW is closed and track switches 3 and 3a are in the normal position; power-off relay POSR is energized; signal control relays 2RHR and 4LHR and electric lock windings 2M and 4M are deenergized; and red lamp R of each signal is lighted.

As shown in the drawing, the primary windings of transformers 1 and the local windings 9 of relays 2RATR and 4LATR are constantly connected with terminals BX and CX.

Both a pick-up circuit and the stick circuit are closed for relay 2TSR. The pick-up circuit which is closed passes from terminal BX, through contact 13 of lever 2V, and winding 9 of relay 2TSR to terminal CX. The stick circuit passes from terminal BX, through contact 15 of relay 2TSR, and winding 9 of relay 2TSR to terminal CX. A pick-up and a stick circuit are also closed for relay 4TSR. The pick-up circuit for this relay passes from terminal BX, through contact 16 of lever 4V, and winding 9 of relay 4TSR to terminal CX. The stick circuit for this relay passes from terminal BX, through contact 18 of relay 4TSR, and winding 9 of relay 4TSR to terminal CX.

The pick-up and stick circuits are also closed for relay POSR. The pick-up circuit for this relay passes from terminal BX, through contacts 19 and 20 of relays 2TSR and 4TSR, respectively, and the winding of relay POSR to terminal CX. The stick circuit for this relay passes from terminal BX, through contact 21 of relay POSR, and the winding of relay POSR to terminal CX.

The normal energizing circuit for mechanisms 3W and 3AW, now closed, passes from terminal BX, through contact 22 of lever 3V closed in the left-hand or N position, contact 23 of lever 2V closed in the N position, mechanisms 3W and 3AW in multiple, contact 24 of lever 4V closed in the N position, and contact 25 of lever 3V closed in the left-hand or N position, to terminal CX.

The circuit by which red lamp R of signal 2R is lighted passes from terminal BX, through the back point of contact 26 of relay 2RHR, and red lamp R of signal 2R to terminal CX. A similar circuit is closed for red lamp R of signal 4L passing from terminal BX, through the back point of contact 27 of relay 4LHR, and lamp R of signal 4L to terminal CX.

I shall assume that the leverman desires to permit an eastbound train to move over switch 3 in the normal position along the lower track. He will therefore move lever 2V to the R position, completing the energizing circuit for relay 2RHR, passing from terminal BX, through contact 28 of lever 2V, contact 29 of relay 2TSR, and the winding of relay 2RHR to terminal CX. Relay 2RHR will therefore now open the circuit for red lamp R at the back point of its contact 26 and, at the front point of its contact 26, will close the circuit for lamp Y of signal 2R, passing from terminal BX, through the front point of contact 26, and lamp Y of signal 2R to terminal CX.

If the leverman should now desire to return lever 2V to its normal position before a train arrives on section 2RAT, he will move lever 2V as far as the D position, thus opening at contact 28 the circuit previously traced for relay 2RHR. With relay 2RHR deenergized, a circuit will now

be complete for energizing magnet 2M of lever 2V, passing from terminal BX, through contacts 2RHR-30 and 2RATR-31, contact 34 of lever 2V, and winding 2M to terminal CX. With winding 2M energized, dog 10 will be raised out of engagement with lug 12, permitting the leverman to complete the return of lever 2V to the N position.

I shall now assume that the leverman again 10 clears signal 2R as before, that a train arrives on section 2RAT, and that the leverman then decides to return lever 2V to the normal position. As before, he will return lever 2V as far as the D position, in which dog 10 will engage lug 12 15 and prevent further movement of lever 2V toward the N position. With relay 2RATR now deenergized on account of the train occupying section 2RAT, the circuit previously traced for magnet 2M will be open at contact 2RATR-31. The leverman will therefore complete a second 20 circuit by operation of a time element device 2TE which, upon the lapse of a measured period of time, closes its contact, completing the second circuit, passing from terminal BX, through contact 2RHR-30, contact of time element device 2TE, contact 34 of lever 2V, and electric lock winding 2M to terminal CX.

I shall next assume that the leverman, as before, clears signal 2R, and that a train then enters section 2RAT and passes signal 2R into section 2T. I shall further assume that while the train is in section 2T, the leverman returns lever 2V toward the N position. With the train occupying section 2T, relay 2TSR will now be deenergized, and hence a third circuit will be completed for winding 2M as soon as the lever reaches the D position, this circuit passing from terminal BX, through contacts 2RHR-30, 2TSR-32, and POSR-33, contact 34 of lever 2V, and winding 2M to terminal CX. The movement of lever 2V will therefore be interrupted at the D position only long enough for winding 2M to lift dog 10 out of engagement with lug 12. The leverman can then complete the return of 45 lever 2V to the N position.

I shall now assume that the leverman clears signal 2R, as before, and that a train again enters section 2RAT, and that while the train occupies section 2RAT the source of power fails, and hence all parts of the apparatus are deenergized. I shall further assume that while the power is off, the leverman returns lever 2V as far as the D position. If now the source of power is restored, relays 2RATR and 4LATR will be energized immediately. Relay POSR being now deenergized on account of track relays 2TSR and 4TSR having been deenergized, a second pick-up circuit is completed for winding 9 of relay 2TSR, passing from terminal BX, through contact POSR-14, and winding 9 of relay 2TSR to terminal CX. A second pick-up circuit will also be completed for relay 4TSR, passing from terminal BX, through contact 11 of relay POSR, and winding 9 of relay 4TSR to terminal CX. With relays 2TSR and 4TSR thus energized, the pick-up circuit previously traced will again be completed for relay POSR, which will then again complete its own stick circuit previously traced. With the train still occupying section 2RAT, the circuit first traced for winding 2M will be open at contact 2RATR-31, and with relay 2TSR now energized, the third circuit traced for winding 2M will be open at contact 2TSR-32, and hence the leverman will again complete the circuit

traced through the contact of time element device 2TE.

It follows that, on account of contact POSR-33 being included in the third circuit traced for winding 2M, winding 2M will not 5 become energized immediately, when the power source is restored, on account of relay 2TSR being at that time deenergized, and thus causing possibly an unsafe condition.

I shall next assume that the leverman again 10 clears signal 2R, and that a train again enters section 2RAT, and that the source of power also again fails. I shall further assume that the leverman does not change the position of lever 2V, and that the power then again comes on. 15 With lever 2V still in the R position, the circuit previously traced for relay 2RHR will be closed as soon as relay 2TSR becomes energized when the power comes on, causing relay 2RHR to be energized and signal 2R to be cleared without 20 further delay.

From the foregoing description and the accompanying drawing, it follows that, with apparatus embodying my invention, if the power goes off of an interlocking system for a brief 25 period when a train is occupying the approach section to the rear of a signal, the approach locking means cannot be energized falsely on account of the detector track section relay being deenergized, when the power is restored. Also, 30 with apparatus embodying my invention, if the power fails in an interlocking system while a train occupies an approach section to the rear of a signal while the signal is clear, the signal will again clear as soon as power is restored, 35 without any action by the leverman if he has left the signal lever in the reverse position.

Although I have herein shown and described only one form of apparatus embodying my invention, it is understood that various changes 40 and modifications may be made therein within the scope of the appended claims without departing from the spirit and scope of my invention.

Having thus described my invention, what I 45 claim is:

1. In combination, a plurality of railway tracks divided into a plurality of track sections, a track circuit including a track relay for each of said sections, a plurality of track switches in said 50 sections interconnecting said tracks, locking means when deenergized preventing operation of said switches, a power-off relay, a common source of electrical current for energizing said track circuits and said locking means and also said 55 power-off relay, a pick-up circuit for said power-off relay controlled by a front contact of each of said track relays, a stick circuit for said power-off relay for retaining said power-off relay in the picked up condition at all times except 60 when said source of current fails, and means controlled by said power-off relay in the picked up condition and by back contacts of said track relays for at times energizing said locking means.

2. In combination, a stretch of railway track 65 including a track switch, traffic responsive means, a power-off relay, locking means which in the deenergized condition prevents operation of said switch, a single source of electrical current for energizing said traffic responsive means and said 70 power-off relay as well as said locking means, means controlled by traffic conditions on said stretch for energizing said traffic responsive means when said stretch of track is unoccupied and for deenergizing said traffic responsive means 75

- when said stretch of track becomes occupied, means controlled by said traffic responsive means in the energized condition for energizing said power-off relay, means for then retaining said power-off relay in the energized condition until said source of current fails, and means controlled by said power-off relay in the energized condition and by said traffic responsive means in the deenergized condition for energizing said locking means.
3. In combination, a section of railway track including a switch, a track circuit for said section including a track relay, a power-off relay, locking means which when deenergized prevents operation of said switch, a common source for supplying electrical current for energizing said track circuit and the energizing circuits for said power-off relay and said locking means, a pick-up circuit for said power-off relay controlled by a front contact of said track relay, a stick circuit for said power-off relay controlled only by a front contact of said power-off relay, and a circuit controlled by a front contact of said power-off relay and by a back contact of said track relay for energizing said locking means.
4. In combination, a section of railway track including a switch, a two-element track relay comprising a track element and a local element, a track circuit for said section including said track element, a power-off relay, a signal for governing traffic movements into said section, a manual control device having a normal and a reverse position, locking means which when deenergized prevents return of said manual control device to the normal position, a common source for supplying electrical current for energizing said track circuit and the energizing circuits for said power-off relay as well as said locking means, a first and a second pick-up circuit for the local element of said track relay controlled by said manual control device in the normal position and by a back contact of said power-off relay respectively, a stick circuit for the local element of said track relay controlled by only a front contact of said track relay, a pick-up and a stick circuit for said power-off relay controlled by a front contact of said track relay and by a front contact of said power-off relay respectively, a circuit for energizing said locking means controlled by a front contact of said power-off relay in series with a back contact of said track relay, means controlled by said manual control device in the reverse position for clearing said signal, and means for operating said switch from one of its extreme positions to the other only if said manual control device is in the normal position.
5. In combination, a stretch of railway track, a power-off relay, a signal for governing traffic movements into said stretch, a manual control device having a normal and a reverse position, a track relay controlled by traffic conditions in said stretch and having a first and a second pick-up circuit controlled by said manual control device in the normal position and by a back contact of said power-off relay respectively, a stick circuit for said track relay controlled by a front contact of said track relay, a pick-up circuit for said power-off relay controlled by a front contact of said track relay, a stick circuit for said power-off relay controlled by only a front contact of said power-off relay, a common source for supplying electrical current for energizing the pick-up and stick circuits for said track relay and said power-off relay, and means controlled by said manual control means in the reverse position and by a front contact of said track relay for clearing said signal.
6. In combination, a stretch of railway track including a switch, a track circuit for said stretch including a track relay, a signal for governing traffic movements into said stretch, a power-off relay, a manual control device having a normal and a reverse position, means controlled by said manual control device in the reverse position for clearing said signal, locking means which when it is deenergized prevents return of said manual control device to the normal position, a pick-up and a stick circuit for said power-off relay controlled by front contacts of said track relay and said power-off relay respectively, a circuit controlled by a front contact of said power-off relay and by a back contact of said track relay for energizing said locking means, a common source of electrical current for energizing said track circuit and the energizing circuits for said power-off relay and said locking means, and means controlled in part by said manual control device in the normal position for operating said switch between its extreme positions.

CHARLES H. LAY. 50
